UNITED STATES PATENT OFFICE.

CHARLES E. POPE, OF HOLYOKE, MASSACHUSETTS, ASSIGNOR TO GREAT NORTHERN PAPER COMPANY, OF MILLINOCKET, MAINE, A CORPORATION.

AUTOMATIC PAPER-MACHINE.

1,283,888.

Specification of Letters Patent.

Patented Nov. 5, 1918.

Application filed January 31, 1917. Serial No. 145,678.

To all whom it may concern:

Be it known that I, CHARLES E. POPE, a citizen of the United States of America, residing at Holyoke, in the county of Hampden and State of Massachusetts, have invented certain new and useful Improvements in Automatic Paper-Machines, of which the following is a specification.

This invention relates to automatic paper machines and particularly to improved means for automatically transferring the web from one drying cylinder to another.

Paper machines of the class described are characterized in that the web, at the start or after any break in the process of making the paper, is carried automatically through the machine as distinguished from leading the web through the machine by hand. For example, the web is arranged to jump the distance from one drier to another and is thus transferred by its own momentum. Certain difficulties have from time to time appeared in the operation of such machines in practical use, and one of the main aims of this invention is to provide means to insure to an added degree the automatic transfer of the paper from drier to drier.

An object of this invention is to provide in a paper machine, in combination with the drying cylinders thereof, means whereby the forward end of the traveling web may be automatically guided or fed in a definite path to pass it from drier to drier.

Another object of the invention is to provide in a machine of the class described, means to direct a blast of air on each side of the forward end of a web as it passes from one cylinder to another, the arrangement being characterized in that said means act in opposed relation on the web and in such a manner that the latter is guided by the action of balanced forces or in the path of least resistance in its travel between driers.

Other objects and advantages will appear in the description to follow and will be pointed out in the appended claims.

The invention, in an embodiment at present preferred, is shown for illustrative purposes in the accompanying drawings, in which—

Figure 1 is a diagrammatical view showing a series of drying cylinders with the invention applied thereto;

Fig. 2 is a partial side elevational view showing the mounting of the parts indicated in Fig. 1, so far as is necessary to an understanding of the invention by those skilled in the art;

Fig. 3 is a diagrammatical view on an enlarged scale, showing in detail the manner in which a web is automatically guided and transferred from drier to drier;

Fig. 4 is a cross sectional view taken on the line 4—4 of Fig. 3;

Fig. 5 is a diagrammatical view showing the invention as applied to another arrangement of drying cylinders; and

Fig. 6 is a modification of the arrangement shown in Fig. 5.

Referring to these drawings: The invention has been illustrated as applied to a high speed automatic paper machine of the type disclosed in my prior Patent No. 1,274,712, granted Feb. 6, 1917. The invention, is, however, capable of general application and is shown and described in connection with a machine of the type mentioned, merely as an illustrative example of one specific use of the invention.

As is well known by those skilled in the art, the web, at the start or after any break in the process of making the paper, is usually carried through the machine and fed to and through the drying cylinders by hand. Rather than handling the full width of the web, the general practice is to form a ribbon, usually at one side of the wire, which is carried through the machine and afterward leads a web of full width for the normal operation.

Referring to Figs. 1 and 2, the lower apron 10 carries the web 11 from the last press rolls (not shown) to a guide roll 12 adjacent the periphery of the first drier 13 and the apron returns over other rolls 12. In line with the upper roll 12 and between it and the first drier 13 is a guide roll 14 provided with a doctor 15. Above and a little beyond roll 14 is a horizontally arranged pipe 16 connected to a source of air under pressure. The web 11, traveling at high speed, jumps the distance between rolls 12 and 14 and is forced downwardly by a blast of air from pipe 16 into the bight of the first drier 13 and its apron 17, whereupon the ribbon is pulled around roll 14. This manner of leading the web from the

press rolls to the first drier is claimed and more fully described in my prior Patent No. 1,183,113, granted May 16, 1916, and is shown and described herein simply for illustrative purposes, as any other suitable means may be employed as desired.

The arrangement of the drying cylinders shown in Figs. 1 and 2 is claimed and fully described in my first-named prior patent. 10 This arrangement of the driers will be briefly described herein so far as is necessary to an understanding of the present invention. Each lower drier 13 of a series is located with its axis vertically or substantially so, below that of its companion upper drier 18 in the upper series. The upper and lower driers are also arranged only a small distance apart or in such a way that the forward end of the web or ribbon 11, as it 15 travels rapidly through the machine, may jump from the lower drier into the bight of the upper drier and its associated apron 19, without climbing any appreciable distance. The aprons 17 and 19 are carried by suitable 20 guide rolls 20 and 21, respectively, and the lower roll 21 directs its apron 19 to the upper drier 18, so that, as the ribbon 11 leaves the drier 13, it will jump to the apron 19 and be transferred to the upper drier. This 25 result is achieved by the momentum of the web, and the latter is aided and guided in its transfer by means constituting the main feature of my present invention in one preferred embodiment as will be later described.

30 The web or ribbon 11 is stripped from the drier 18 by a doctor 23 as it is traveling vertically or substantially so and downwardly in a direction substantially tangential to the lower drier 13 of the succeeding set. The 35 upper left hand guide rolls 20 and lower right hand guide rolls 21 are mounted close to their respective cylinders, and the web, therefore, may pass freely and automatically downward into the bight of the lower drier 40 13 and its associated apron 17.

45 After the ribbon has been started through the machine, a web of full width is formed and the normal operation ensues. The doctors 23 are then preferably moved to a retracted position. Below the doctors 23 are other devices which function to clean the driers 18 of the foreign matter which ordinarily gathers as a fine film upon the periphery of the cylinders. Similar devices 50 are provided for the lower driers 13, as indicated. These devices comprise doctor blades 24 bent into substantially the form shown to form troughs. Each trough is mounted upon a pipe 25 and is connected 55 with the interior thereof in a manner disclosed in the first-named prior patent, to which reference is made for a more complete disclosure. For the present purposes, it will suffice to state that the pipes 25 are connected to a suitable vacuum pump whereby the

film of dust and lint collected from the driers may be automatically removed from the troughs.

The structure so far described is substantially the same as that disclosed in the first-named prior patent. The present invention is more particularly concerned with improved devices which facilitate the automatic transfer of the web from one drier to another, by stripping the web from one 70 drier and directing it into the bight of the other drier and its associated apron.

These improved devices will now be described. Referring to Fig. 1, horizontally arranged pipes 28 are mounted adjacent 80 lower driers 13 and between the lower right hand guide rolls 21 and the devices 24 for the lower driers. Other similarly arranged pipes 29 are provided adjacent the left hand guide rolls 20 and between them and the 85 driers 13, or these pipes 29 may be arranged beyond said guide rolls and be directed to sweep across the top thereof, as shown in my United States Patent No. 992,688, May 16, 1911. The detailed manner of mounting pipes 28 is shown in Fig. 4 and the mounting of pipes 29 is similar. As there indicated, the pipes preferably extend from one side of the machine inwardly a relatively short distance only, since they ordinarily act only upon the narrow ribbon formed at the start or after any break in the process of making the paper. Each pipe is provided with a row of perforations, as shown in Fig. 4, and I have found that, if 100 the perforations are made one sixteenth of an inch diameter and spaced one-half of an inch on centers, satisfactory results are obtained. Obviously, pipes 28 may be provided with other forms or arrangements of 105 openings as desired, but the described arrangement has been found advantageous. Pipes 28 are connected by unions 30 to valves 31, as shown in Fig. 4, and it is to be noted that by reason of the "union" connection, 110 angular adjustment of each pipe may be conveniently made, as desired.

115 Valves 31 and similar valves 32 provided for pipes 29 are connected by a pipe 33 to a source of air under pressure and in pipe 33 is a valve 34 which controls the entire series of perforated pipes.

120 At the start of the machine valve 34 is open and blasts of air issue in opposite directions from pipes 28 and 29, as indicated in Fig. 3. The web 11, as it reaches the top of the lower drier 13 is stripped therefrom by the blast from pipe 28 and blown toward the upper drier 18. The web 11, as it is thus forced to the left (as viewed in Fig. 3), 125 is met by a blast of air from pipe 29 which tends to hold the web away from the upper drier. The force of the blast from pipes 28 and 29 is regulable by the valves 31 and 32 and is so adjusted that the web 6 is guided 130

into the bight of the upper drier 18 and its associated apron 19. The automatic transfer of the web or ribbon from a lower to an upper drier by the momentum of the web 5 is thus aided by the stripping action of pipes 28 and the guiding action of the pipes 28 and 29 working in coöperative relation.

To secure the desired coöperative action of the pipes 28 and 29 under various conditions, the valves 31 and 32 are provided to permit adjustment of the pressure of the air blasts and the unions 30 for angular adjustment of the air blasts. When once properly adjusted, these valves may be fixed in a 15 suitable manner, as by removing the hand wheels, for example, and the valve 34 only is used to control the entire series of pipes, as a starting and stopping means for the blasts. After the ribbon 11 has been led 20 through the machines as described, the blasts from pipes 28 and 29 are no longer necessary and valve 34 may then be closed.

The invention is not limited in application to the described arrangement of drying cylinders and is capable of general use. 25 The invention may be used with the ordinary and well-known staggered arrangement of drying cylinders, as shown diagrammatically in Fig. 5. A pipe 28' may be located between each guide roll 40, for the apron 41 of the upper driers 42, and each lower drier 43 and a pipe 29' may be arranged beyond each guide roll 44 for the apron 45 of the lower drier 42 to direct the 30 air across the apron 45 as it bends over the roll which will tend to strip the ribbon therefrom if it starts to follow the apron all as indicated in Fig. 5 or my prior patent referred to above. These pipes may be constructed, mounted, and connected in a manner analogous to that already described in connection with Fig. 1 to operate in a similar way to strip the web 11 from a lower drier and direct it into the bight of the upper 45 drier and its associated apron.

If desired, means in addition to the air blasts from pipes 28 or 28' may be employed to strip the web 11 from the lower driers 13 or 43. As an illustrative example, the 50 means shown in Fig. 6 may be used, it being understood that the parts in this figure are brought closely together to save space in the figure. A brush 45' is mounted to rotate between the lower drier 43 and the guide roll 40 and brushes lightly against the former. This brush is suitably driven as by belt connections (not shown) from roll 40, to rotate in an opposite direction to the lower drier and at a surface speed somewhat 55 in excess of that of the web. I have found that, if the surface speed of the brush is about twenty-five per cent. faster than that of the web, satisfactory results will be obtained. Brush 45' may be mounted in any 60 suitable manner, and it may extend in-

wardly from one side of the machine in a manner analogous to pipe 28, a sufficient distance to cover the ribbon. The pipe 28' may be replaced by a nozzle 46 through which a blast of air is directed through the bristles on the upper part of the brush. The web 11 is stripped from the drier 43 by the rapidly revolving brush, and thrown toward the drier 42, as indicated by dotted lines in Fig. 6, and as it travels upwardly is thrown 70 into the bight of the upper drier and its apron 41 by the blast of air from nozzle 46 and an additional blast from a pipe similar to pipe 29' if desired. Although the arrangement described has been illustrated in 75 connection with the well known staggered arrangement of driers, it may equally well be applied to the arrangement of driers shown in Fig. 1.

The arrangement of the pipes 28 and 29 to direct blasts of air in opposite directions on each side of the web is important and advantageous. The pressure of the air blasts is capable of variation as is also the direction thereof. By properly adjusting the direction and force of the blast from one pipe with relation to the direction and force of the blast from the other pipe, the web may be carried in a clear unobstructed path from a lower drier into the bight of the upper drier and its associated apron. The web is thus carried in a definite path which may be defined as the line of neutrality at every point of which the force from one blast is exactly balanced by that from the other. 95

The invention has been described in a preferred form for illustrative purposes, but the scope of the invention is defined by the appended claims rather than by the foregoing description. 100

What I claim is—

1. In a paper making machine, upper and lower driers, aprons therefor, means to loosen the web from a lower drier and throw it toward the upper drier, and means to deflect the web from the latter, said first and last named means arranged to act in opposition on the faces of the web to guide the latter into the bight of the upper drier and its associated apron. 110

2. In a paper making machine, upper and lower driers, aprons therefor, and means to direct a blast of air on each face of the web as it travels from drier to drier, said means being arranged in opposed relation and adapted to direct and guide the web in a definite path between driers, whereby the traveling web may be guided into the bight of the upper drier and its associated apron. 120

3. In a paper making machine, upper and lower driers, aprons therefor, and pneumatic means arranged to act on each face of the web as it travels from drier to drier, said means arranged to act in opposed relation to direct and guide the web by the action of 130

balanced forces in a definite path from one drier to another.

4. In a paper making machine, an upper and a lower drier, aprons therefor, pneumatic means to loosen the web from the lower drier and throw it toward the upper drier and a second pneumatic means arranged to act on the opposite face of the web from the first-named means, all constructed and arranged so that the web may be directed and guided from the lower to the upper drier in a definite path wherein the force of one means is balanced by that of the other.

5. In a paper making machine, the combination of a set of drying cylinders, aprons therefor, means to guide the web to the driers, the apron on a bottom drier being arranged to hold the web against the drier until it reaches a point where it travels substantially horizontally on the upper surface of the drier, pneumatic means to strip the web from the bottom drier, the apron on a companion top drier being arranged to form with its drier an entrance in line with the substantially horizontally traveling web

stripped from the lower drier, whereby the web may be transferred automatically from a lower to an upper drying cylinder, and a second pneumatic means, arranged to act on the web in opposition to the first-named means, whereby the web may be guided in a definite path by the action of balanced forces thereon.

6. In a paper making machine, the combination with upper and lower drying cylinders, aprons therefor, means to guide the latter to and from the cylinders, arranged so that the web in passing from one cylinder to another is exposed on both sides for a portion of its travel, and a directing means on each side of said portion, said directing means being arranged to act on opposite faces of the forward end of a web during its transition from one cylinder to another and to be balanced one against the other so that the web is guided in a definite channel, whereby the web may be transferred automatically by its momentum aided by said directing means.

CHARLES E. POPE.
